UNITED STATES PATENT OFFICE.

FRANK H. PLAISTRIDGE, OF LOS ANGELES, CALIFORNIA.

WASHBOILER.

1,201,983.

Specification of Letters Patent. Patented Oct. 17, 1916.

Application filed February 28, 1916. Serial No. 80,831.

To all whom it may concern:

Be it known that I, FRANK H. PLAISTRIDGE, a citizen of the United States, residing at Los Angeles, California, have invented 5 a new and useful Washboiler, of which the following is a specification.

My object is to make a wash boiler bottom having a flat supporting surface and having heat accumulators and conductors 10 pressed upwardly, so as to increase the heating capacity and so as to prevent the laundry from lying flat upon the bottom; and my invention consists of the novel features herein shown, described and claimed.

Figure 1 is a side elevation of a wash boiler parts being broken away and shown in section to illustrate the application of the principles of my invention in the construction of the bottom. Fig. 2 is a top plan 15 view of a fragment of the bottom. Fig. 3 is an enlarged sectional detail of the bottom on the line 3—3 of Fig. 2, and illustrating the laundry resting on the apexes of the heat conductors with water in the valleys under 20 the laundry.

The wash boiler 1 may be of any of the well known or desired forms, except as to the bottom 2 which embodies the principles of my invention. The bottom 2 is formed 25

from a flat sheet. The heat accumulators and conductors 3 are pressed upwardly from the flat surface 4, are regularly spaced in rows, those of one row being staggered relative to the next row, and are circular in plan and semi-circular in elevation, and form 30 zig-zag valleys 5 between their apexes 6. When a quantity of water 7 is placed in the boiler it will fill the valleys 5 and the laundry 8 will rest lightly upon the apexes 6. When the boiler 1 is set over a fire heat will 35 collect in the chambers 9 under the apexes 6 and the water in the valleys 5 will boil up through the laundry 8. In this way the efficiency of the heat transmitting surface is increased about 25 per cent. The laundry 40 45 does not lie as on a flat surface and can not be over-heated as long as there is plenty of water.

I claim:

A wash boiler bottom formed of a flat 50 sheet having a series of upwardly extending semi-spherical projections arranged in staggered relation to each other thereby forming zig-zag valleys between the projections.

FRANK H. PLAISTRIDGE.

Witness:

JAS. GROENDYKE.
